UNITED STATES PATENT OFFICE

2,512,382

METHOD OF FORMING COLLAPSIBLE CONTAINERS

William A. Ringier, Wayne, Pa., assignor to The Gardner Board and Carton Co., a corporation of Ohio

Application September 8, 1945, Serial No. 615,191

5 Claims. (Cl. 93—51)

1

This invention provides a method and device for forming and setting up liquid tight cartons or containers of the knock down type made from cardboard, paperboard or other suitable foldable sheet material.

Cartons or containers embodying the invention may be prefabricated in the form of flat, cut and creased blanks and may be set up either manually or on semi-automatic equipment by a sequence of assembly operations resulting in a self-locking carton which does not require gluing, stapling or riveting operations to maintain it in set-up condition.

A representative form of carton set-up according to the invention briefly comprises a bottom to which side walls are hingedly connected along fold lines forming the bottom edges of the carton. The side walls are interconnected by pairs of bellows or gusset panels hingedly connected to the side edges of the side walls, whereby liquid proofness of the container is attained. Reference is made to my copending application Serial No. 613,843, filed August 31, 1945 and entitled Containers for illustrative types of cartons which may be set-up according to my invention.

In the assembly of the carton the gusset panels are folded face to face and overlie the side walls adding materially to the strength of the walls. Lock flaps hingedly connected along the top edge of the carton overlie the folded gusset panels and hold them in carton assembled position. The lock flaps are secured in folded over position by folding the lock flaps at the corners of the carton. Each lock flap thus extends around a corner of the carton and resists folding up into a position in which the gusset panels would be released. The lock flaps in addition to maintaining the container in assembled position, reinforce the top edge of the container and provide a rim to which various forms of covers may be connected or locked.

Cartons and containers formed according to the present invention are admirably suited for the packaging of frozen foods, ice cream and the like, particularly since they may be shipped and stored in collapsed condition, be set up when needed, and may be knocked down and flattened out for disposal after use without necessity of tearing of container panels, pulling of staples or other time consuming or inconvenient operations.

The invention further provides a semi-automatic jig on which carton blanks may be folded and set up. The jig briefly comprises a plurality of side wall panel folding members mounted on a pivoted base. A plunger adapted to engage the

2

bottom panel of the carton blank is movable into the space between the side wall forming members and folds the side wall panels into a position upright with respect to the bottom panel. The plunger is pivoted coaxially with the support and permits rotation of the folded carton blank in the jig for the purpose of securing the side walls in set-up position by successive folding of the lock flaps and placing of the gusset panels or corners thereunder.

The various objects, features and advantages of the invention will appear more fully from the detailed description which follows, accompanied by drawings showing, for the purpose of illustration, preferred embodiments of the invention. The invention also consists in certain new and original steps of assembly as well as features of construction and combination of parts hereinafter set forth and claimed.

20 Although the characteristic features of the invention which are believed to be novel will be particularly pointed out in the claims appended hereto, the invention itself, its objects and advantages and the manner in which it may be carried out may be better understood by referring to the following detailed description and the accompanying drawings forming a part thereof in which:

Fig. 1 is a plan view of a flat carton blank from which a carton embodying features of this invention may be made, the inside surface of the blank facing the observer;

Fig. 2 is a perspective view of a representative form of semi-automatic jig for setting up a carton from a flat blank according to the method provided by this invention;

Fig. 3 is a perspective view showing the blank of Fig. 1 inserted between the folding mechanism of the jig of Fig. 2, parts of the jig not necessary for the understanding of the step being omitted;

Fig. 4 illustrates a first folding operation performed on the blank of Fig. 1;

Fig. 5 shows the blank of Fig. 1 after a further folding operation in which the gusset panels at the side edges of the container blank are brought into face to face position;

Fig. 6 illustrates the folding of a first securing flap and the folding of a first pair of gusset panels;

Fig. 7 illustrates the folding of a second securing flap which holds the first pair of gusset panels in position and the folding of a second pair of gusset panels, the support and plunger of the jig being turned about their pivots by the operator;

Fig. 8 illustrates a further step in the progres-

sive assembly of the container, the folding of a third securing flap to lock the second pair of gusset panels and the folding of the third pair of gusset panels into side wall overlying position;

Fig. 9 illustrates the folding of the last securing flap which holds the third pair of gusset panels in place preparatory to the tucking of the last pair of gusset panels underneath the first folded securing flap; and

Fig. 10 is a perspective view of the completed carton.

In the following description and in the claims various details will be identified by specific names for convenience. These names, however, are intended to be as generic in their application as the art will permit. Like reference characters refer to like parts in the several figures of the drawings.

In the drawings accompanying, and forming part of, this specification, certain specific disclosure of the invention is made for the purpose of explanation, but it is understood that details may be modified in various respects without departing from the broad aspect of the invention.

The blank A shown in Fig. 1 is substantially rectangular in outline resulting in a minimum of waste of material. The blank may be cut and scored from a large sheet or roll of paperboard or other suitable foldable material on an automatic cutting and scoring machine. Only one side of the blank need be coated or otherwise treated to attain liquid resistance of the stock and only one side of the blank need be decoratively finished or imprinted since one surface of the blank forms the interior surface of the assembled container and the reverse surface forms the outside.

Figure 1 shows the blank "A" in a position in which the inside surface faces the observer. The blank comprises a rectangular bottom panel 11 bounded by fold lines 12, 13 and 14 and 15 forming bottom edges in the completed carton. The fold lines 12, 13, 14 and 15 intersect at the four corners of the bottom panel and extend beyond the corners to the outer edges of the blank. Side wall panels 16, 17, 18 and 19 are hingedly connected to the bottom panel 11 along the fold lines 12, 13, 14 and 15 respectively. The fold lines 12, 13, 14 and 15 bound the side wall panels at the sides and form side edges in the finished container.

A pair of gusset panels 20 and 21 connected along a diagonal fold line 22 are hingedly secured to the side wall panels 16 and 19 along the fold lines 15 and 12 respectively. The gusset panel 20 has a free outer edge 23 and the gusset panel 21 has a cut outer edge 24 of limited length. A pair of gusset panels 25 and 26 connected along a diagonal fold line 27 is hingedly secured to the side panels 18 and 17 along the fold lines 13 and 15 respectively. The gusset panel 25 has a free outer edge 28 and the gusset panel 26 has a cut edge 29 of a limited extent.

A third pair of gusset panels 30 and 31 interconnected along a diagonal fold line 32 is hingedly connected to the side panels 17 and 13 along the fold lines 14 and 13. The gusset panel 30 has a free outer edge 33 and the gusset panel 31 has a cut edge 34 of limited length.

A fourth pair of gusset panels 35 and 36 interconnected along a diagonal fold line 37 is hinged to the side panels 18 and 16 along the fold lines 12 and 14 respectively. The gusset panel 35 has a free edge 38 and the gusset panel 36 has a relatively short-cut edge 39.

A joint lock flap 40 common to both the gusset panel 36 and the side wall panel 16 is hingedly connected to the two panels along a top fold line 41 which may be in alignment with the cut edges 39 and 23 or may be slightly spaced therefrom but parallel thereto in order to accommodate two thicknesses of gusset panels in the assembled container. The lock flap 40 is subdivided by the fold line 44 into a portion 40' hinged to the gusset panel 36 and a portion 40'' hinged to the side wall panel 16.

A similar joint lock flap 42 common to the gusset panel 21 and the side wall panel 19 is hingedly connected thereto along a top fold line 43. The lock flap 42 is subdivided into portions 42' and 42'' by the fold line 12 extending thereto across.

A further joint lock flap 44 common to the gusset panel 26 and to the side wall panel 17 is hingedly connected thereto along a top fold line 45. The lock flap 44 is subdivided into portions 44' and 44'' by the fold line 15 extending thereto across.

The corresponding lock flap 46 subdivided by the fold line 13 into portions 46' and 46'' is hingedly connected to both the gusset panel 31 and the adjoining side wall panel 18.

The gusset panels 20 and 21 are further creased along fold lines 48 and 49 extending parallel to fold lines 15 and 12, respectively. The distance between the fold lines 15 and 48 and the fold lines 12 and 49 is equal to, or slightly larger than, the width of the narrow side wall panel 16. A similar pair of additional fold lines 50 and 51 runs across the gusset panels 30 and 31.

The blank A as shown in Fig. 1 is ready for assembly into hollow container form by a series of folding operations without the necessity of gluing, stapling or otherwise mechanically adhering the panels together as will be presently described. The blank may be stored and shipped in flat condition or it may be folded twice along parallel fold lines, for example, along fold lines 12 and 13, so that the side wall panels 45 to either side of the fold lines overlie the top surface and the bottom surface of the bottom panel 11, respectively. Thus folded, the blank is reduced to approximately one-third of its width, which is advantageous where a saving of space is of importance.

The blank A may be formed and folded into hollow container form either manually or on a semi-automatic jig shown in Fig. 2.

The illustrated form of jig comprises a base 55 carrying uprights or posts 56 and 57 joined by a crossbeam 58 secured to the posts at 59 and 60.

The base 55 carries a support 61 pivoted on the base at 62 for rotation with respect to the base. Two upright plates 63 and 64 are secured to the support 61 to serve as folding and supporting members for opposite side walls of the blank "A." A second pair of plates 65 and 66 are tiltably mounted on the support 61 at 67 and 68. The tiltable plates 65 and 66 have extensions 69 and 70 extending substantially at right angles with respect to the plates. Stops 71 and 72 support the tiltable plates 65 and 66 in the swing out position into which the plates tend to move due to 70 their unbalance. A force excited on the extensions 69 and 70 causes the plates 65 and 66 to tilt about their respective tilt axes 67 and 68 to assume an upright position with respect to the fixed plates 63 and 64. The upright plates 63, 64, 65, and 66 form four upright walls which are

somewhat spaced at the four vertical edges for reasons which will presently appear.

A plunger 73 is mounted for rotation on the cylindrical end 74 of a square rod 75. The rod 75 is vertically slideable in a bearing 76 in the crossbeam 58. Weights 77 and 78 counterbalance the plunger 73 and rod 75. The weights 77 and 78 are suspended from cables 79 and 80 guided over rollers 81, 82, 83 and 84, and attached to the rod 75 at 85 and 86. The plunger fits into the space between the upright plates 63, 64, 65, and 66 with sufficient play to allow for the thickness of the blank to be folded. Inserted between the upright plates 63, 64, 65 and 66, the plunger 73 may be rotated together with the support 61 due to a coaxial arrangement of the rod 75 with the pivot 62 of the support 61.

In order to form a carton from a carton blank A the flat blank is placed on the top edges of the fixed plates 63 and 64 so that the fold lines 14 and 15 lie slightly inside the space defined by the folding plates 63 and 64 as shown in Fig. 3.

The plunger 73 is then moved downwardly engaging with its bottom the surface of the bottom panel 11 of the blank and folding the blank A about the fold lines 14 and 15 as shown in Fig. 4.

After a certain amount of downward travel the plunger 73, with the bottom panel 11 of the blank thereunder, engages the L-shaped extensions 63 and 70 of the tiltable plates 65 and 66 causing the plates to tilt gradually into upright position with respect to the support 61 on which they are mounted. The tilting of the plates 65 and 66 causes the side wall panels 17 and 16 to fold about their respective fold lines 13 and 12, while simultaneously the four pairs of gusset panels 20, 21; 25, 26; 30, 31; and 35, 36 are folded face to face and outwardly with respect to the plunger 73.

The folded blank now assumes the form shown in Fig. 5 and is ready for the folding and securing of the folded gusset panels in locking position.

The locking of the four pairs of gusset panels is preferably done progressively, and may proceed as follows:

The side wall panel 17 and the gusset panel 26 are first aligned in order to straighten the fold line 45 along which the lock flap 44 is hinged. The lock flap 44 is then folded outwardly about the fold line 45 to overlie the top portion of the side wall panel 17 and of the gusset panel 26. The pair of gusset panels 26 and 27 lying face to face is then swung about the fold lines 13 and 15 lying in substantial alignment until the pair of gusset panels overlies the outside surface of the side wall panel 19. This position is illustrated in Fig. 6. In the resulting structure the side wall nearest to the observer is of single thickness where the side wall panel 19 is exposed and of triple thickness where the pair of gusset panels 26 and 27 overlie the side wall panel 19. The resulting reinforcement makes the side wall 19 extremely sturdy.

After the folding of the gusset panels 26 and 27 over the side wall panel 19 the two portions 44' and 44'' of the lock flap 44 have assumed an angular position with respect to each other which prevents unfolding of the sections 44' and 44''.

The assembly of the container then proceeds by moving the pair of gusset panels 20 and 21 about the side fold lines 12 and 15 into alignment with the side wall panel 16. In order to perform this operation the support and plunger are preferably turned about their pivots as illustrated in

Fig. 7. In this position the sections of the top fold line 41 along which the lock flap portions 40' and 40'' are hinged are aligned permitting folding of the entire lock flap 40 outwardly so that lock flap portion 40'' overlies lock flap portion 42' on the previously folded gusset panel 21 and lock flap portion 40' overlies the outside surface of the gusset panel 36. The folded gusset panels 36 and 35 are then swung about the fold lines 12 and 14 forming a side edge of the container into a position in which the folded gusset panels 36 and 35 overlie the side wall panel 18. This folding operation causes folding of the two portions of the lock flap 40 about the fold line 14 whereby the portion 40'' overlying the gusset panels 20 and 21 is fixed in position. Thus folded the structure appears in Fig. 8.

In the further stages of the assembly the gusset panels 31 and 30 are aligned with the side wall panel 18, the lock flap 46 common to the side wall panel 18 and the gusset panel 31 are folded outwardly to overlie the last folded pair of gusset panels 36 and 35, locking the gusset panels 36 and 35 in position. The gusset panels 30 and 31 are then swung about the fold lines 14 and 13 forming a side edge of the container until the gusset panels 30 and 31 overlie the side wall 17 as shown in Fig. 9.

The lock flap 44 common to the side wall panel 17 and the gusset panel 26 are then folded outwardly to overlie and lock the last folded pair of gusset panels 30 and 31. The gusset panels 26 and 25 are then swung about the aligned fold lines 13 and 15 until they overlie the side wall panel 19. Finally the folded gusset panels 25 and 26 are tucked under the lock flap 42'' whereby the assembly of the container is completed.

The container may then be removed from the jig by lifting the plunger 73 out of the container and then lifting the container off the side wall supporting plates 63, 64, 65, and 66 of the jig.

The finished container is shown in Fig. 10. It has a rectangular bottom panel and four side walls reinforced by pairs of gusset panels. Each pair of gusset panels is locked by lock flaps which in addition reinforce the top edge of the container and provide a locking rim to which a cover of suitable construction may be secured.

The container may be knocked down simply by pulling any of the four folded gusset panels from underneath its locking flap whereafter the container may be flattened out progressively.

The invention thus provides a method and device for forming liquid tight containers of extremely simple and rugged construction which may be set up, filled and closed either manually by unskilled labor or be handled on semi-automatic equipment. The container is very sturdy due to the reinforcement of the side wall and the top edge. It possesses the advantage of being easily knocked down after use.

No glue or staples are required for assembling the container which is entirely self-locking due to its peculiar manner of assembly.

The invention is of course not limited to the specific form of blank shown in the drawings nor to the specific form of jig. The form of the blanks may be modified in various ways without departing from the peculiar features of the method of assembly above described. Cartons having square or polygonal bottom panels and a corresponding number of side walls may be set up according to this invention. Thus various modifications of the blank as well as numerous other changes, additions, omissions and substitutions

may be made by persons skilled in the art without departing from the spirit and teaching of the invention.

What is claimed is:

1. The method of setting up a carton from a flat blank having a bottom panel, side wall panels hinged thereto, pairs of gusset panels connecting the side wall panels, and lock flaps hinged to the top edges of the side wall panels and the gusset panels, each lock flap being common to a side wall panel and an adjacent gusset panel, the method comprising, folding the side wall panels into a position substantially at right angles with respect to the bottom panel; folding the gusset panels of one corner over the adjacent side wall panel; and simultaneously folding the lock flap hinged to said last named gusset panels over said last named gusset panels, the lock flap being bent at the carton corner; folding the gusset panels of the next corner over the respective side wall panel; and simultaneously folding the lock flap associated with said last named gusset panels over the previously folded gusset panels, whereby the previously folded gusset panels are locked in position; folding the gusset panels of the succeeding corners in like manner; and tucking the last remaining gusset panels under the lock flaps associated with the first folded gusset panels.

2. The method of securing in set-up position adjacent walls of a collapsible folding carton having a bottom, side walls, gusset corners between adjacent side walls, and lock flaps each common to one side wall and the adjacent portion of a gusset corner, which includes erecting said side walls, and folding down a lock flap over a side wall; and the gusset corner to which it is attached, and bending the folded lock flap at the carton corner by folding the gusset corner against an adjacent wall, and repeating these operations progressively for a plurality of said side walls.

3. The method claimed in claim 2 including the step of tucking the last folded gusset corner under the first folded lock flap.

4. The method of securing in set-up position adjacent walls of a collapsible folding carton, having a bottom, side walls, gusset corners between adjacent side walls, and lock flaps each common to one side wall and the adjacent portion of a gusset corner, which includes the steps of erecting said side walls; folding a gusset cor-

ner to a position substantially coplanar with the side wall bearing a lock flap in common with said gusset corner, folding down the common lock flap over the side wall and the gusset corner, bending the folded lock flap about the carton edge by folding the gusset corner against an adjacent wall, repeating these steps for a plurality of successive side walls, and tucking the last folded gusset corner under the first folded lock flap.

5. The method of setting up a carton from a blank having a bottom panel, side wall panels articulated thereto, pairs of gusset panels connecting the side wall panels, and lock flaps articulated to the top edges of the side wall panels and the gusset panels, each lock flap being common to a side wall panel and one adjacent gusset panel, including the steps of folding the side wall panels into a position substantially at right angles with respect to the bottom panel, folding the gusset panels of one corner to a position substantially coplanar with one of the adjacent side wall panels, folding down the lock flap articulated to said last mentioned side wall panel, and then folding the said gusset panels over onto the other of the adjacent side wall panels, folding the gusset panels of the next successive corner to a position substantially coplanar with said last mentioned side wall panel, folding down the lock flap articulated to the said last mentioned side wall panel over the first folded gusset panels, folding the gusset panels of the said next successive corner over onto a third side wall panel, whereby the first folded gusset panels are locked in folded position, folding successively the gusset panels of the remaining corners in like manner; and tucking the last remaining gusset panels under said first folded lock flap.
